TUMBLER BEADER

Robert J. Miner and Walter A. Timm, Toledo, Ohio, assignors to Owens-Illinois, Inc., a corporation of Ohio

Filed Nov. 26, 1963, Ser. No. 326,005

4 Claims. (Cl. 118—239)

This invention relates to an apparatus for applying ceramic color to the bead surface of glass tumblers or the like.

More specifically, this invention relates to an apparatus for applying decorating material in liquid form to the upper edge or bead of glass tumblers in which the ware moves continuously on a straight line conveyor past the decorating position without interruption of the movement of the ware.

In the past it has been necessary in decorating the bead edge of glassware to hold the ware in a chuck, rotate the ware and apply the decorating coating to the bead surface as the ware is rotated relative to the applicator.

Other systems have been tried, in which moving belts are used to apply a ceramic coating to the bead surface of the ware, but again in this system it was necessary that the ware be capable of rotating relative to the ink applying surface of the belts.

With the foregoing in view, it is an object of this invention to provide apparatus for applying an inorganic or organic color medium in liquid form to the bead surface of tumblers or like articles.

It is an additional object of this invention to provide apparatus which applies a ceramic color to the bead or upper edge of articles in which the articles are conveyed continuously in a linear path without the necessity of interrupting the movement when applying the decoration.

Other and further objects will be apparent from the following description taken in conjunction with the annexed sheet of drawing, wherein:

FIG. 1 is a top plan view of the apparatus of the invention;

FIG. 2 is a side elevational view of the apparatus of FIG. 1, and

FIG. 3 is a detailed view on a large scale of a portion of the apparatus of FIG. 1.

With reference to the drawing, a continuously driven conveyor belt 10 running in a horizontal plane carries the ware 11 thereon in spaced-apart intervals beneath the mechanism for applying the ink to the bead edge of the ware.

The ink applying mechanism comprises a base 12 (only a portion of which is shown) which may be supported from the floor as a stand or it may be portable, in the sense that it may have castors so that it can be moved into position adjacent the moving conveyor belt. The base 12 carries four upstanding bushings 13 fixed at its upper surface with the upper ends of the bushings being joined together by a plate 14. The bushings 13 are adapted to serve as guides for four vertical rods 15 which are joined together at their upper ends by a mounting plate 16. The mounting plate 16, as best shown in FIG. 1, takes a generally rectangular form and adjacent its center, as shown in FIG. 2, carries a thrust bearing 17 on its undersurface. The thrust bearing 17 rotatably receives the end of a threaded shaft 18. The threaded shaft 18 extends downward through a complementarily threaded bushing 19 fixed to the plate 14. The lower end of the shaft 18 carries a crank arm 20 fixed thereto which serves as a means for rotating the shaft 18 to effectively raise and lower the plate 16 relative to the base 12.

In this manner the plate 16 is adjusted in height. The plate 16 carries two shaft bearings 21 and 22 which are adapted to receive a horizontal shaft 23. One end of the

2

shaft 23 extends through the bearing 22 and when the base is positioned relative to the conveyor, as shown in FIGS. 1 and 2, the end of the shaft will extend over the surface of the conveyor 10. The extending end of the shaft 23 extends through a pair of shaft bearings 24 and 25 which in turn are fixed to a platform 26.

The platform 26 is generally rectangular in plan view and extends parallel to the length of the conveyor. The platform carries a motor 27 fixed thereto to the right of the supporting shaft 23. The motor 27, through suitable gearing, drives a shaft 28 to which a pair of pulleys 29 and 30 are fixed. The platform 26 has two vertical side plates 31 and 32 fixed to the end thereof opposite the end supporting the motor 27. The two side plates 31 and 32 serve to rotatably support a pair of horizontal shafts 33 and 34. The shaft 33 carries a drum 35 fixed thereto between the two side plates 31 and 32. The diameter of the drum is such that a portion of its peripheral surface extends below the plane of the platform 26, it being understood that the platform has an opening in the bottom thereof corresponding to the position of the drum to permit the drum to rotate relative thereto. The platform 26 also carries an inking material trough 36 within which the surface of an inking roller 37 mounted on the shaft 34 is adapted to turn. A doctor blade 38 fixed to a support 39 has its outer edge in wiping contact with the surface of the roller 37.

It should be pointed out that the roller 37 runs in close proximity to the surface of the drum 35 and it can readily be seen that upon rotation of the drum 35 in the direction of the arrow shown thereon in FIG. 2, ink will be transferred from the roller 37 to the surface of the drum 35. The drum 35 and inking roller 37 are both driven by the motor 27 through the belts 40 and 41 which are respectively in engagement with the pulleys 29 and 30. A belt tension take-up pulley 42 is adjustably mounted with respect to a vertically extending support 43 so that the tension in the belt 40 may be maintained at a proper level.

Thus it can be readily seen that a continuous supply of ink will be supplied to the drum 35 by reason of its running in close proximity to the roller 37. With the particular drive shown, the roller 37 will be rotated in the same direction as the drum 35 and with its lower periphery submerged in the ink contained in the trough 36 ink will be picked up on the roller 37, spread relatively thin by the doctor blade 38 and then transferred to the drum 35 during its rotation past the roller 37.

As the ware 11 is moved by the conveyor beneath the drum 35, ink carried by the drum will be transferred to the top surface of the ware.

As previously explained, the platform 26 may be raised and lowered as desired by rotation of the threaded shaft 18. This adjustment is provided to accommodate the apparatus for glass tumblers or glassware of different heights. This adjustment is somewhat gross, in that it is not capable of very close, fine adjustment and in order to provide such fine adjustment, an adjustable stop mechanism, specifically illustrated in FIG. 3, is provided.

An angle bracket 44 fixed to the mounting plate 16 carries an end 45 thereof which terminates in close proximity to the side plate 31 adjacent the forward end of the side plate 31. A bracket 46 connected to the side plate 31 extends vertically downward with a portion 47 thereof extending horizontally in overlying relationship with respect to the end 45 of the bracket 44.

It should be pointed out that as the tumblers move beneath the drum 35, the platform 26 pivots about the shaft 23 and the particular arrangement and distribution of weight on the platform 26 is counter-balanced slightly toward the drum carrying end so that a certain amount of force is applied by the drum to the upper surface of the tumbler or glassware as it is moved beneath the drum.

In order to prevent the platform 26 from tilting too far beyond the horizontal, a threaded bolt 48 is provided which extends through aligned openings in the portion 47 of bracket 46 and in the end 45 of the bracket 44. A helical spring 49 is mounted in surrounding relationship with respect to the bolt 48 and extends between the head of the bolt and the upper surface of the portion 47 of the bracket 46. A second helical spring 50 is mounted in surrounding relationship with respect to the bolt 48 and extends between the undersurface of the end 45 of the bracket 44 and a thumb screw 51 which is threaded on the bolt 48.

Inasmuch as the bracket 46 is fixed to the platform 26, downward movement of the platform is limited to the extent of its contacting of the portion 47 by the end 45 of the bracket 44. This contact thus serves to define the lowest position of the drum periphery in relation to the conveyor surface. In order to provide a finer adjustment to this position, an adjusting screw 52, which is threaded through the portion 47 of the bracket 46, be adjusted with its end in contact with the end 45 of the bracket 44. Thus it can readily be seen that turning of the adjusting screw 52 will provide a fine adjustment of the initial height of the drum surface with respect to ware passing thereunder.

As the ware contacts the drum 35, the drum will be forced upwardly and cause the platform 26 to pivot about the shaft 23. The upward movement of the drum end of the platform 26 is regulated to the extent of the force exerted on the bracket 46 by the springs 49 and 50. Obviously, the spring 49 will be somewhat compressed and as the bolt 48 is moved upwardly the spring 50 would also be somewhat compressed. However, these springs in turn will assure the return of the drum to its initial position preparatory to being contacted by the next article to be treated.

The roller 37 will normally have a rubber-like surface and the ware contacting surface of the drum 35 may also be of rubber. However, it was found satisfactory to use a drum having a plain aluminum surface and it was found that such a drum would carry sufficient ceramic color or ink to provide an adequate coating to the bead or upper surface of the ware. In the operation of the device it is important that the drum be rotated by the motor 27 at a peripheral speed which is equal to the lineal speed of the conveyor 10. While not shown, it should be readily appreciated that synchronous drive mechanism, for assuring that the peripheral speed of the drum and the conveyor belt speed are the same, is conventional in the article handling art.

In summary, it can be seen that applicants have provided an apparatus for applying ceramic color or ink to the upper edge of articles which are continuously moving in succession on a conveyor by the use of a driven drum serving as the ink transfer means. The particular mechanism described above is adjustable in the sense that it may be used to apply ink to ware of different heights and the ware carried by the conveyor need not have any further support as is customary in other devices utilized for applying ink to the beads of tumblers and like articles,

Various modifications may be resorted to within the spirit and scope of the appended claims.

We claim:

1. Apparatus for applying ceramic color to the mouth-defining rim surfaces of tumblers or the like comprising, means for moving a plurality of tumblers in upright position in a straight line, a horizontal shaft, a frame and means thereon mounting said shaft with one end extending outwardly over the line of moving tumblers and spaced vertically thereabove, a platform, means rockably mounting said platform on the outwardly extending end of said shaft so as to be disposed in a longitudinally and overlying rockable relation to said line of moving the tumblers, a motor mounted on said platform longitudinally thereof and at one side of the pivot, a rotatable drum means rotatably mounting said drum on the platform longitudinally thereof at the other side of said pivot, said drum defining a peripheral decorating surface that is in an overlying relationship with the line of tumblers and engageable with their rim surfaces as they move longitudinally beneath said platform, means drivingly connecting said motor to rotate said drum, a supply of ceramic color carried on said platform, inking means including an inking roller rotatable in said ceramic color and positioned between said supply thereof and said decorating surface of the drum for transferring the color to said decorating surface, the platform being counterweighted so as to rock in the direction for lowering the decorating surface of the drum into engagement with the rim surface of the tumblers therebeneath, means connected to said frame for raising and lowering said shaft with respect to said line of moving tumblers, stop means on the frame and engageable with said platform for limiting the rocking movement of said platform, and resilient means connected between said platform and said stop means normally urging said platform into contact with said stop means.

2. The apparatus of claim 1 further including adjustable means between the platform and stop means for adjusting the spacing therebetween when in abutting relationship.

3. The apparatus of claim 1 wherein the means for urging said platform into contact with said stop means comprises a bracket fixed to the platform, a bolt passing through both the stop means and the bracket, and a spring surrounding the bolt in contact with the bolt head and the bracket.

4. The color applying apparatus defined in claim 1, wherein said peripheral decorating surface of the drum comprises a plain aluminum surface.
